US00D838190S

(12) **United States Design Patent** (10) **Patent No.:** **US D838,190 S**
(45) **Date of Patent:** **** Jan. 15, 2019**

(54) **SENSOR MODULE**

(71) **Applicant:** **DELTA ELECTRONICS, INC.**,
Taoyuan (TW)

(72) **Inventors:** **Pin-Chen Lai**, Taoyuan (TW);
Chen-Yu Hung, Taoyuan (TW);
Sheng-Chan Tu, Taoyuan (TW);
Yuan-Ping Hsieh, Taoyuan (TW)

(73) **Assignee:** **DELTA ELECTRONICS, INC.**,
Taoyuan (TW)

(**) **Term:** **15 Years**

(21) **Appl. No.:** **29/605,488**

(22) **Filed:** **May 26, 2017**

(57) **CLAIM**

The ornamental design for a sensor module, as shown and described.

DESCRIPTION

FIG. 1 is a perspective view of a sensor module showing our new design;

FIG. 2 is another perspective view thereof;

FIG. 3 is yet another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken line portions in the drawing views are included to show unclaimed subject matter only and form no part of the claimed design.
